(57) CLAIM

The ornamental design for a surgical undergarment as shown and described.

DESCRIPTION

FIG. 1 is a perspective view of a first embodiment of a surgical undergarment showing my new design.

FIG. 2 is a front view thereof.

FIG. 3 is a rear view thereof.

FIG. 4 is a right view thereof.

FIG. 5 is a left view thereof.

FIG. 6 is a top view thereof.

FIG. 7 is a bottom view thereof.

FIG. 8 is a perspective view of a second embodiment of a surgical undergarment showing my new design.

FIG. 9 is a front view thereof.

FIG. 10 is a rear view thereof.

FIG. 11 is a right view thereof.

FIG. 12 is a left view thereof.

FIG. 13 is a top view thereof; and,

FIG. 14 is a bottom view thereof.

The broken lines in the figures show portions of the design which form no part of the claimed design.

1 Claim, 10 Drawing Sheets
